CLAIM

The ornamental design for a floor lamp, as shown and described.

DESCRIPTION

FIG. 1 is a top, front, right side perspective view of a floor lamp, showing my new design; FIG. 2 is a bottom, rear, left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of the portion 9 in FIG. 1; FIG. 10 is an enlarged view of the portion 10 in FIG. 1; FIG. 11 is an enlarged view of the portion 11 in FIG. 1; FIG. 12 is an enlarged view of the portion 12 in FIG. 2; FIG. 13 is an enlarged view of the portion 13 in FIG. 2; and, FIG. 14 is an enlarged view of the portion 14 in FIG. 2. The evenly dashed broken lines illustrate portions of the floor lamp and form no part of the claimed design. The unevenly dashed broken lines define the boundaries of enlarged views and form no part of the claimed design.
